UNITED STATES PATENT OFFICE

130,483

DESIGN FOR A TABLE

Charles A. Lindberg, Rockford, Ill., assignor of
one-half to Robert W. Skinner, Rockford, Ill.

Application May 17, 1941, Serial No. 101,000

Term of patent 14 years

To all whom it may concern:

Be it known that I, Charles A. Lindberg, a citizen of the United States, residing at Rockford, in the county of Winnebago and State of Illinois, have invented a new, original, and ornamental Design for a Table, of which the following is a specification, reference being had to the accompanying drawings, forming part thereof.

In the drawings:

Fig. 1 is a perspective view of a table embodying my new design, the drawer being shown closed and the entire lower portion of the table being indicated in dotted lines;

Fig. 2 is a side elevational view thereof;

Fig. 3 is a perspective view of the table showing the drawer opened; and

Fig. 4 is a top plan view thereof.

The dominant features of my design reside in a substantially circular top drum-type table having a drawer substantially of the configuration illustrated, and as best shown in Figs. 3 and 4 of the drawings.

I claim:

The ornamental design for a table, substantially as shown and described.

CHARLES A. LINDBERG.
